Application January 28, 1948, Serial No. 4,798

1 Claim. (Cl. 126—76)

1

The present invention relates generally to solid fuel heaters. More particularly the invention relates to that type of solid fuel heater which is known in the art as a smokeless heater, serves as a space heating medium or instrumentality and as its principal components or parts comprises: (1) a vertically elongated, box-like shell having a normally closed air-tight ash pit or chamber in the lower portion thereof, a combination fuel and combustion chamber in its central portion, and a grate between the two chambers; (2) an outlet duct for the products of combustion leading upwards from a point directly above the grate to a flue adjacent the top wall of the shell; (3) a duct arrangement opposite the outlet duct for admitting outside primary air into the upper part of the combination fuel and combustion chamber and outside primary air into the lower part of such chamber; and (4) a horizontally extending conduit which is located directly inwards of the lower or inlet end of the outlet duct and is connected and arranged to deliver outside secondary air into the lower part of the combination fuel and combustion chamber.

It has heretofore been proposed in connection with the manufacture or fabrication of a smokeless solid fuel heater of the aforementioned type to form the secondary air conduit of cast metal and to provide in the lower portion of the conduit a single horizontal, full length discharge slot which faces inwards and downwards and serves to discharge the secondary air so that it flows part way through the fuel in the lower part of the combination fuel and combustion chamber. In practice it has been found that a cast metal secondary air conduit is subject to the objection that during high capacity fuel consumption of the heater the lower part thereof, i. e., the part having the single horizontal, full length downwardly and inwardly facing discharge slot, becomes heated to such an extent that it either burns out or warps. If the lower slot defining part of the secondary air conduit burns out or warps to an appreciable extent the efficiency of the heater is pronouncedly reduced and it is usually necessary to replace the conduit.

The primary object of the invention is to provide in connection with a smokeless solid fuel heater of the type and character under consideration simple means whereby the secondary air conduit is cooled to such an extent during heater operation that it does not burn out or warp and hence necessitate replacement.

Another object of the invention is to provide

a smokeless solid fuel heater of the last mentioned character wherein the cooling means for the secondary air conduit is in the form of an air passage arrangement which is disposed in the lower part of the conduit and is adapted to have outside air flow through it in order to effect the desired cooling of the conduit.

A further object of the invention is to provide a smokeless solid fuel heater which is generally of new and improved construction and, due to its design and construction, possesses high efficiency and extremely long life.

Other objects of the invention and the various advantages and characteristics of the present fuel heater will be apparent from a consideration of the following detailed description.

The invention consists in the several novel features which are hereinafter set forth and are more particularly defined by the claim at the conclusion hereof.

In the drawings which accompany and form a part of this specification or disclosure and in which like numerals of reference denote corresponding parts throughout the several views:

23. Figure 1 is a rear perspective view of a smokeless solid fuel heater embodying the invention;

24. Figure 2 is a vertical longitudinal section illustrating in detail the construction, design and arrangement of the outlet duct, the primary air duct arrangement and the secondary air conduit.

25. Figure 3 is a vertical transverse section taken on the line 3—3 of Figure 2 and showing in detail the air passage arrangement which is formed in the lower part of the secondary air conduit and serves in response to flow of outside air therethrough to effect cooling of such part of the conduit; and

26. Figure 4 is a horizontal section on the line 4—4 of Figure 2.

The smokeless heater which is shown in the drawings constitutes the preferred form or embodiment of the invention. It is designed for use as a space or room heater and may be fired with bituminous coal, coke, anthracite coal, wood, or composition fuel blocks. As its principal components or parts the heater comprises a shell 10, an outlet duct 11, a primary air duct arrangement 12, a secondary air conduit 13, and a grate 14. All of the parts, with the exception of the secondary air conduit 13, are of standard or conventional construction.

The shell 10 is vertically elongated and has a box-like contour or configuration. It is preferably formed of plate or heavy sheet metal and consists of a bottom wall 15, a front wall 16,

a back wall 17, a pair of side walls 18 and 19 and a top wall 20. The front wall 16 and the back wall 17 are arranged in opposed relation, and the side walls 18 and 19 extend between and at right angles to the front and back walls and have the side margins thereof suitably connected to the side margins of the last mentioned walls. The lower margins of the front, back and side walls are suitably secured to the marginal portions of the bottom wall. As shown in the drawings, the shell 10 is deeper than it is wide. In other words, it is elongated from front to back. The top wall 20 is rectangular and has its marginal portions suitably secured to the upper marginal portions of the front, back and side walls of the shell. The lower portion of the shell interior constitutes an ash pit or chamber 21 and the central interior portion of the shell constitutes a combination fuel and combustion chamber 22. These two chambers are separated by the grate 14. The upper portion of the chamber 22 constitutes a space or magazine for the solid fuel and the lower portion of the chamber serves as a combustion space. A receptacle 23 for receiving and collecting ashes may, if desired, be positioned in the ash pit 21 beneath the grate 14. Access to the ash pit is provided by way of a rectangular opening 24 in the lower portion of the shell side wall 19. This opening is normally closed by an imperforate hinged door 25 and is sufficiently wide to permit the receptacle 23 to be inserted into, and removed from, the ash pit 21. Access to the upper portion of the chamber 22, i. e., the fuel space, is provided by way of a rectangular opening 26 in the shell side wall 19. This opening is located an appreciable distance above the door-closed opening 24 and is normally closed by way of a hinged imperforate door 27. When the latter is swung into its open position solid fuel may be introduced into the chamber 22 via the opening 26.

The outlet duct 11 serves as a discharge medium for the products of combustion that result from burning of the solid fuel in the combustion space of the chamber 22. It embodies a vertically extending branch 28 along the central and upper portions of the front wall 16 of the shell and a horizontally extending branch 29 directly beneath the shell top wall 20. The vertically extending branch of the outlet duct is defined by said central and upper portions of the front wall 16 together with the secondary air conduit 13 and a plate 30. The conduit 13 is spaced a comparatively small distance inwards from the central portion of the shell front wall 16 and extends between, and is secured to, the shell side walls 18 and 19, as hereinafter described more in detail. During operation of the heater the products of combustion travel horizontally over the grate 14 in the direction of the shell front wall 16 and then, after flowing under the secondary air conduit 13, pass upwards through the vertically extending branch 28 of the outlet duct 11. The plate 30 is located for the most part above the conduit 13 and is disposed slightly inwards of, and in parallel relation with, the upper portion of the front wall 16 of the shell 10. The side margins of the plate 30 are bent at right angles to form flanges which are suitably secured to adjacent portions of the shell side walls 18 and 19. The plate 30 defines with the adjacent portion of the shell front wall the upper end of the vertically extending branch 28 of the outlet duct 11. The horizontally extending branch 29 of the outlet duct is defined by the

shell top wall 20 and a subjacent plate 31. The latter is forwardly and downwardly inclined to a slight extent and defines the top of the combination fuel and combustion chamber 22. The front marginal portion of the plate 31 is secured to the upper marginal portion of the plate 30 and the side marginal portions of the plate 31 are bent upwards at right angles to form flanges which are suitably secured to the upper portions of the shell side walls 18 and 19. The rear end of the horizontally extending branch 29 of the outlet duct 11 is connected to a flue 32 by way of a tubular nipple 33 on the upper portion of the shell back wall 17. When the heater is in operation the products of combustion, after flowing upwards through the vertically extending branch 28 of the outlet duct, flow rearwards through the horizontally extending branch 29 and are then discharged to outside atmosphere by way of the flue 32.

The duct arrangement 12 serves to admit primary air into the upper part of the combination fuel and combustion chamber 22 and primary air into the lower part of such chamber. It is disposed directly inwards of the back wall 17 of the shell 10 and consists of an upwardly extending upper branch 34 and a downwardly and inwardly inclined lower branch 35. The upper branch 34 of the duct arrangement 12 is defined by the upper portion of the shell back wall 17, a substantially vertically extending plate 36 and a horizontally extending partition forming plate 37. It has the upper end thereof open and in communication with the upper part of the fuel space of the chamber 22. The plate 36 is spaced inwards from the upper portion of the shell back wall and has its side margins suitably secured to the adjacent portions of the shell side walls 18 and 19. The upper margin of the plate 36 is disposed a comparatively small distance below the plate 31 in order to effect communication between the upper end of the upper branch 34 of the duct 12 and the upper part of the fuel space of the combination fuel and combustion chamber 22. The partition forming plate 37 is connected to, and extends outwards from, the lower marginal portion of the plate 36 and serves to divide or separate the upper and lower branches of the duct arrangement 12. The primary air that is supplied to the upper part of the fuel space of the chamber 22 enters the lower end of the upper branch 34 of the duct arrangement by way of a plate valve controlled hole 38 in the central portion of the shell back wall 17. The primary air, after flowing upwards through the upper branch 34, flows downwards through the fuel in the chamber 22 and has a twofold purpose in that it prevents clogging of the fuel in the fuel space of the chamber 22 and also serves, together with the primary air that is introduced into such chamber by way of the lower branch 35, to promote combustion of the portion of the fuel that directly overlies the grate 14. The lower branch 35 of the duct arrangement 12 is defined or formed by a pair of spaced apart downwardly and inwardly inclined plates 39 and 40. The plate 39 is located an appreciable distance beneath the partition forming plate 37 and extends downwards and inwards from the shell back wall 17. The side margins of the plate 39 are suitably secured to the adjacent portions of the side walls of the shell. The plate 40 overlies the plate 39 and extends downwards and inwards from the inner marginal portion of the partition forming plate

31. The side margins of the plate 40 are suitably secured to the adjacent portions of the shell side walls and the lower marginal portion of said plate is spaced from the lower marginal portion of the plate 39 and defines therewith a primary air outlet for the lower branch 35 of the duct arrangement. As best shown in Figure 2 such primary air outlet is located directly above the grate 14 and serves to cause the primary air passing therethrough to flow over the grate 14 in the direction of the lower end of the vertically extending branch 28 of the outlet duct 11. Primary air is introduced into the upper end of the branch 35 by way of a plate valve controlled hole 41 in the back wall 17 of the shell.

The conduit 13, which, as hereinbefore pointed out, assists in defining the lower end of the vertically extending branch 28 of the outlet duct 11, is preferably in the form of a two-piece metal casting. It extends between the shell side walls 18 and 19 and consists of an outer piece 42 and a complementary inner piece 43. The outer piece 42 extends substantially vertically and has the upper marginal portion thereof secured against the outer face of the lower marginal portion of the plate 30 by way of bolts or other suitable attaching devices (not shown). The central and lower portions of the outer piece 42 of the secondary air conduit are shaped to form a full length enlargement 44. The inner piece 43 of the conduit consists of a side wall 45, a top wall 46, and a pair of end walls 47. The side wall 45 is disposed in opposed and spaced relation with the outer piece 42, and the top wall 46 is connected to, and projects outwards from, the outer marginal portion of the side wall 45 and has its outer marginal portion in abutment with the inner face of the lower marginal portion of the plate 30 and secured thereto by the aforesaid bolts or other suitable attaching devices. The end walls 47 extend at right angles to the side and top walls 45 and 46 and abut against, and are suitably secured to, the adjacent portions of the shell side walls 18 and 19. Secondary air is introduced into the manifold 13 from the space directly around the shell 10 of the heater by way of circular holes 48 in the shell side walls 18 and 19 and registering circular holes 49 in the upper portions of the end walls 47 of the inner piece 43 of the conduit. The lower part of the full length enlargement 44 of the outer piece 42 and the lower marginal portion of the side wall 45 of the inner conduit piece 43 are spaced apart and shaped so as to form a single horizontal, full length discharge slot 50 whereby the secondary air is introduced into the lower part of the combination fuel and combustion chamber 22. The slot 50 is inwardly and downwardly inclined and serves to discharge the secondary air so that it flows part way through the fuel in the lower portion of the combustion space of the chamber 22. The secondary air that is introduced by way of the slot 50 in the conduit 13 assists the primary air in effecting complete combustion to the end that the heater is smokeless. By reason of the fact that the products of combustion are at their highest temperature when they pass around the lower part of the secondary air conduit 13 the enlargement 44 at the lower marginal portion of the outer piece 42 of the conduit is subjected to extremely high heat conditions.

With the view of preventing burning out and warping of the lower part of the conduit the enlargement 44 is provided with a passage arrange-

ment 51 whereby outside air is permitted to flow or circulate therethrough for cooling purposes. As best shown in Figure 3, the passage arrangement 51 comprises a horizontally extending lower branch 51a, a horizontally extending upper branch 51b and a vertically extending branch 51c. These three branches are formed in the full length enlargement 44 of the outer piece 42 of the secondary air conduit 13. The lower branch 51a is substantially cylindrical. It extends throughout the entire length of the aforesaid enlargement and has open ends which communicate with outside air by way of registering circular holes 52 in the shell side walls 18 and 19. The horizontally extending upper branch 51b of the passage arrangement overlies the lower branch 51a and extends throughout the entire length of the enlargement 44 and has open ends which communicate with outside air by way of registering holes 52a in the shell side walls 18 and 19. Preferably the upper branch is rectangular in cross section. The vertically extending branch 51c is located midway between the ends of the enlargement 44 and extends between, and serves to connect, the central portions of the lower and upper branches 51a and 51b by way of the vertically extending branch 51c. After flowing into the central portion of the upper branch 51b the outside air flows outwards through the end portions of the upper branch and is discharged to atmosphere via the holes 52a in the shell side walls. The passage or circulation of air through the passage arrangement 51 is continuous and provides such cooling of the lower portion of the conduit that it, as well as the upper part, is effectively and efficiently prevented from burning out or warping. The passage, in effect, provides for a continuous circulation of air and results in such reduction in temperature of the conduit that the latter possesses a life as great as that of the other parts of the heater and hence does not necessitate or require replacement.

The grate 14 is disposed between the ash pit 21 and the combination fuel and combustion chamber 22 and consists of a rectangular frame 53, a pair of side by side grate bars 54 and a dump grate 55. The grate bars and dump grate are suitably supported by the frame so that they may be rocked back and forth in a manner well understood in the art.

The herein described smokeless solid fuel heater is highly efficient so far as operation is concerned. It possesses extremely long life by reason of the fact that the cast metal conduit 13 for supplying secondary air part way through the bed of fuel on the grate has associated with it effective and efficient cooling means whereby it is precluded from being heated to such a high degree as to cause burning out and warpage. The cooling means consisting of the air passage arrangement 51 is essentially simple in design and does not, to any appreciable extent, increase the cost of manufacture of the heater as a whole. It is self functioning or operating because it works on the natural draft principle and hence does not increase the cost of operation of the heater. By reason of the fact that the conduit has the air passage arrangement 51 it may be made of cast metal instead of cast refractory material.

The invention is not to be understood as restricted to the details set forth since these may be modified within the scope of the appended claim without departing from the spirit and scope of the invention.

Having thus described the invention what we

claim as new and desire to secure by Letters Patent is:

A solid fuel heater comprising an upstanding shell having a normally closed ash pit in its lower portion, a chamber in the form of an upper fuel space and a lower combustion space above the ash pit, and a grate between the chamber and said ash pit, means within the shell forming an outlet duct for the products of combustion located for the most part at one side of said chamber and leading upwards from a point directly above the grate, and means within the shell and at the opposite side of the chamber for delivering primary air so that it flows in a wide stream over the grate in the direction of the lower end of the outlet duct, said outlet duct forming means embodying at its lower end a horizontally elongated cast metal conduit disposed in laterally spaced relation with the primary air delivering means, having the ends thereof connected to receive outside air as secondary air, provided in the lower part thereof with a single horizontal full length discharge slot facing inwards and downwards and serving to discharge the secondary air towards the combustion space, and having on its lower and central parts and at the outer side of and above the slot a full length enlargement, said enlargement having formed therein a passage arrangement closed to the shell and conduit interiors, consisting of a horizontally extending lower branch at the outer side of said slot and with the ends thereof open to outside

air via holes in the shell, a horizontally extending upper branch with its ends open to outside air via holes in said shell and a vertically extending branch between, and in communication with, the central portions of the upper and lower branches, and adapted to have outside air by a natural draft action flow inwards through the open ends of the lower branch, then upwards through the vertically extending branch and then outwards to atmosphere via the open ends of the upper branch and thus effect cooling of the conduit during operation of the heater.
